UNITED STATES PATENT OFFICE.

LOUIS E. BEERS, OF ASPEN, COLORADO.

DISTILLING APPARATUS.

No. 797,255.

Specification of Letters Patent.

Patented Aug. 15, 1905.

Application filed November 14, 1904. Serial No. 232,718.

To all whom it may concern:

Be it known that I, LOUIS E. BEERS, a citizen of the United States, residing at Aspen, in the county of Pitkin and State of Colorado, have invented new and useful Improvements in Distilling Apparatus, of which the following is a specification.

This invention is a distilling apparatus for water, and it is characterized particularly by the fact that the steam condensed is utilized to heat the water in an ordinary domestic hot-water tank, the still being particularly adapted for domestic use.

A further feature of the invention is the provision of a safety device to prevent overheating and explosion due to low water or failure of water-supply.

By reason of these features the invention will be found particularly useful in connection with an ordinary household water-heating apparatus.

The invention is illustrated in the accompanying drawings, wherein—

Figure 1 is an elevation of the apparatus, partly in section. Figs. 2 and 3 are respectively a vertical section and a side elevation of a safety-valve and its casing. Fig. 4 is a plan view of the cover to the tank which controls the feed of water to the water-back of the range.

Referring specifically to the drawings, 6 indicates the water-back or boiler of a range or stove which is utilized to boil the water to be distilled.

7 is an ordinary hot-water tank.

At 8 is indicated a supply-pipe through which water enters into an elevated storage-tank 9, where the height of water is regulated by a float-valve 10 in the pipe 8. Leading from tank 9 is a pipe 11, through which water is supplied to a tank 12, which is located beside and at substantially the same height as the water-back of the range. The flow of water from the pipe 11 to the tank 12 is controlled by a float-valve 13. The tank 12 is connected to the water-back 6 by a pipe 14, and thus the level of water in the water-back 6 and the tank 12 is the same. The float of the valve 13 is so positioned that the level of the water in the water-back is just below the outlet-pipe 15 for the steam. This outlet-pipe leads from the water-back to a coil 16 in the hot-water tank 7, where the steam is condensed and the water escapes through the out-

let 17, where it may be caught in a suitable vessel.

The tank 12 is provided with a safety device which operates in case of an interference with the water-supply, said safety device being constructed as follows: At 18 is indicated a valve casing or fitting containing valves 19 and 20, which are controlled by a float 21, contained in a box 22, located within the tank 12. Water in the tank 12 enters the box 22 by a coil 23, which is open at the lower end. The stem of the T-fitting 18 extends through the cover of the tank 12, as shown. The valves 19 and 20 are respectively opened and closed by the float 21, which is controlled by the rise and fall of water in the tank 12. When the water is at normal or proper height, the valve 19 is open and the valve 20 is closed. This allows free passage of steam through pipe 15 and into the condensing-coil 16. Should the flow of water from tank 9 stop by accident or otherwise while the still is working, the water in tank 12 sinks, and with it the float 21, which closes the valve 19 and opens the valve 20, and consequently changes the course of the steam from the pipe 15 into the coil 23, in which it is condensed by the water remaining in the tank 12 and is used over and over again, thus keeping a supply of water in the water-back. The box 22 is also provided with a whistle 24, which projects through the cover of the tank 12. When in consequence of the movement of the valves 19 and 20 steam enters this box, it blows the whistle, and therefore notifies the persons in hearing of the condition and of the necessity for refilling the tank 12. This refilling is preferably done by hand, for which purpose the cover 25 of the tank 12 is made funnel-shaped with a small hole 26 at the bottom. When water is poured into the cover, it will slowly enter the tank through the hole, providing a gradual flow of water into the water-back, so as not to crack it by sudden inflow of a large quantity of cold water. The pipe 27 is an overflow-pipe from the tank 6 and has therein a flushing-plug 28. The overflow-pipe 27 is also connected to the tank 12 at 29 to take care of any excess of water therein in case the float-valve 13 should become leaky.

It will be seen that the heat contained in the steam generated is utilized in the coil 16 for the purpose of heating the water in the tank 7. A double purpose is thus served, since by the operation of the still a supply of hot wa-

ter is also economically provided. The safety appliance formed by the valves associated with the tank 12 prevents any explosion due to interference with the water-supply, which is normally automatic and requires no attention.

What I claim as new, and desire to secure by Letters Patent, is—

1. In a still, the combination with a boiler, a condenser, and a tank connected to the boiler and having the same water-level, of a steam-pipe connecting the boiler and condenser and having an inlet into the tank, and a float-valve in the tank, controlling said pipe and inlet, and arranged to close the pipe from the boiler to the condenser, and open the inlet to the tank, when the water in the tank and boiler becomes low.

2. In a still, the combination with a boiler and a condenser, and a steam-pipe leading from the former to the latter, of a tank connected to the boiler and having the same water-level, a coil in the tank, open at the lower end and

having a valved inlet from the said steam-pipe at the upper end, and a float in the tank controlling said valve, substantially as described.

3. In a still, the combination with a boiler and a condenser, and a steam-pipe leading from the former to the latter, of a tank connected to the boiler, a casing in the tank, an inlet from the steam-pipe to the casing, valves in said pipe and inlet, the former being normally open and the latter normally closed, a float in the casing controlling said valves and acting to close the pipe, and open the inlet to the casing, in case of low water, and a whistle connected to the casing and sounded by steam therein.

In testimony whereof I have signed my name to this specification in the presence of two subscribing witnesses.

LOUIS E. BEERS.
